UNITED STATES PATENT OFFICE.

CHARLES E. GIERDING, OF WEST HAVEN, CONNECTICUT, ASSIGNOR TO THE
NEW HAVEN CAR REGISTER COMPANY, OF NEW HAVEN, CONNECTICUT.

BALLOT-BOX.

SPECIFICATION forming part of Letters Patent No. 674,404, dated May 21, 1901.

Application filed December 2, 1899. Serial No. 738,956. (No model.)

To all whom it may concern:

Be it known that I, CHARLES E. GIERDING, a citizen of the United States, residing at West Haven, in the county of New Haven and State of Connecticut, have invented certain new and useful Improvements in Ballot - Boxes, of which the following is a specification, reference being had therein to the accompanying drawings.

10 My invention relates to improvements in ballot-boxes of that class which mark each ballot inserted and which automatically count and register the same.

The invention is designed to be attached to 15 a ballot-box in which a stationary ballot-chute is used as distinguished from a ballot-box having a sliding ballot-drawer. Some of the mechanisms, however, are as equally applicable to a drawer ballot-box as to a chute-box.

20 In the ballot-box about to be described a ballot is placed in the ballot-chute and the box-tender releases a crank-handle from a stop-lug upon the side of the ballot-box and rotates the same, which rotation operates all of 25 the mechanisms—that is, closes the ballot-chute, so that another ballot cannot be inserted, draws in the ballot, cancels the ballot by printing a series of characters thereon, counts the ballots by a suitable registering 30 device, rings a bell or operates an audible alarm, and when a complete revolution of the crank-handle has been made the stop-lug, above referred to, prevents the further rotation of the crank-handle until the same has 35 been released.

If a ballot is not presented to the above mechanisms through the chute, the printing, registering, and alarm mechanisms will not be actuated, and the mere rotation of the 40 crank-handle has no effect upon the same.

It is one object of my invention, among other things, to provide a ballot-box with functions substantially as outlined that will be absolutely automatic and of few parts and 45 those of such design and structure that they can be constructed at a small cost and readily assembled and when assembled not liable to be disarranged or thrown out of order.

It is a further object of my invention to attach to the registering mechanism means for resetting the same, whereby all of the indi-

cating-wheels may be returned to zero quickly and with few movements.

To these ends my invention consists of the ballot-box having certain details of construction and combination of parts, as will be hereinafter described, and more particularly pointed out in the claims.

Referring to the drawings, in which like numerals designate like parts in the several views, Figure 1 is a fragmentary side elevation of one form of a ballot-box embodying my improved mechanism, a portion of the side being broken away and the side frames of the interior mechanism removed, but outlined in dotted lines, and the bottom door, used for removing the ballots, swung partly open. Fig. 2 is a plan view of the operating mechanisms removed from the box, the indicating - train and a part of its shaft being taken out. Fig. 3 is an elevation of the same from the rear end; Fig. 4, a transverse section of the same upon line A B of Fig. 3. Fig. 5 is a sectional view of one of the registering-wheels. Fig. 6 is a detailed view of one of the registering-wheel gears and the notched disk which is attached thereto. Fig. 7 is a detailed view of the bell-crank, forming part of the locking mechanism between a registering-wheel and its operating-gear. Fig. 8 is a fragmentary view of the handle end of the crank-handle, the stop-lug, and a portion of the side of the box, the broken lines illustrating the position of the handle when the same is being released from the stop-shoulder and ready to receive another turn. Fig. 9 is a detailed view of the stop-lug. Fig. 10 is a view of the registering-wheel shaft and resetting-knob, with a fragmentary view of a portion of one of the side frames, showing the relative positions of the several parts; and Fig. 11 is a detailed view of the operating-cam.

The mechanism is supported upon braces 2 within a box 1, which performs the double function of being a case to inclose the apparatus and a suitable receptacle for the reception of the ballots, in which they are retained until removed by opening the door 3 at the bottom of the box. In the drawings this door is shown as being partly open. A double cover is provided for the

box, the apparatus-cover 4 being hinged to the box 1 at 5 and having a front side 6, in which is secured a glass plate 7, through which the indicating-wheels are displayed, 5 and the chute-cover 8 being hinged to the apparatus-cover 4 at 9, which cover is open, as shown in Fig. 1, when balloting. After the balloting has ceased, the chute-cover 8 is closed to the position shown by the broken 10 lines in Fig. 1, when the box can be transported from place to place without fear of injury to any of the parts, all of the mechanism being contained therein and free from injury. Any suitable locking devices may be used to 15 securely lock the covers and the bottom door, none of which are shown, they not being material to my invention.

The numerals 10 11 designate the side frames, which are provided with feet 12 12, 20 that rest and are secured upon the braces 2. Jounaled at either end in the said side frames is the shaft 13, which projects through the side of the box 1 and having a crank-handle 14 removably secured thereto, endwise movement 25 of the shaft being prevented by the collars 15 15 outside of the frames. A ratchet 17 upon said shaft and a pawl 16, secured to the side frame and held in engagement with said ratchet by the spring 18, prevents a backward 30 rotation of the said shaft, permitting a movement only in one direction, which is imparted through the crank-handle 14.

The ballot-chute 19 is made, preferably, of sheet metal with upturned sides 20 20 and is 35 fastened at the inner ends to the side frames by means of the lugs 21 and rods 22. A block 23 upon the box 1 supports the outer end of the chute—that is, the portion which projects through the side 6 of the apparatus-cover. 40 Hinged below the inner end of the chute 19 by the lugs 42 upon the rod 24, fastened at one end to the side frame 11 and at the other end to the bracket 41, secured to the opposite frame 10, is the swinging tray 25, which is 45 provided with openings 26 at the front end through the bottom thereof for a purpose hereinafter to be described.

To prevent inserting another ballot in the chute after one has been dropped therein and 50 is passing through the canceling and operating rolls and before the same has dropped into the receptacle below the apparatus, I provide a hinged guard to completely cover the top, sides, and end of all that portion of the chute 55 which projects outside of the box and in view of the voter or box-tender, which guard is automatically operated by the crank-handle 14, any movement of which drops the guard down over the chute and there holds it until 60 the crank-handle returns to its original position, effectually closing the chute and preventing the insertion of another ballot until the guard is again raised and the chute is uncovered. This mechanism consists of a guard 65 27, constructed, preferably, with sheet-metal sides 28 28 and a downwardly-projecting forward end 29, the top being a fine-mesh net-

ting, a rock-shaft 30, journaled at either end in the side frames and to which the guard is secured by the arms 31 31, rock-arm 32, fixed 70 to said shaft 30 and connected by a link 33 with the cam - actuated lever 34, and a spring 35, which is secured to the side frame and an arm 36 and exerts a pressure upon the rock-shaft 30, which tends to hold the 75 guard 27 in its upright position, as shown in Figs. 2 and 4. An angle-plate 116 is fastened to the top side of the rear end of the chute to prevent the insertion of a ballot between the rear end of the guard and the front of the 80 apparatus-cover. Upon the shaft 13 a cam 37 is fixed, having a laterally-projecting flange 40, which is concentric with the said shaft for substantially the whole of its contour and having a depression 38 therein. A cam-roll 85 39 upon the lever 34 lies upon the outside of the cam-flange 40, and when the roll 39 is in the depression 38 the guard is in its upright position, (see Fig. 1;) but when by the rotation of the cam the roll is carried out of the 90 depression and onto the concentric portion of the cam-flange the lever 34 is raised and the link 33 imparts an oscillating motion to the rock-shaft 30 and throws down the guard 27 over the chute, where it is held until the roll 39 again drops into the depression 38 and the spring 35 returns the rock-shaft to its former position, which raises the guard to its upright position, uncovering the chute. When the 95 apparatus is at rest, the roll 39 is always in the depression 38 and the guard is in its upright position; but by the slightest rotary movement imparted to the crank-handle the cam 37 is rotated sufficiently to carry the roll 100 out of the depression, which throws down the guard and covers the chute almost simultaneously with the turning of the crank-handle. 105

The ballot may be canceled by perforating holes therein, by printing characters thereon, or by manipulating it in any other well-known 110 manner; but I prefer to print thereon a series of characters which may be used to designate the town, ward, precinct, &c., where the ballot-box is located, so that if ballots from several districts were to be thrown together 115 into one mass the ballots from each district could be sorted out by simply referring to the cancellation-marks.

The printing device illustrated in the drawings comprises one or more printing-rolls 43, 120 in this case two, loosely journaled upon a shaft 44, fixed at either end in the arms 45 45, extending from the shaft 46, which is journaled in the side frames, inking-rolls 47 47, fixed upon a rod 48, that extends across the 125 open end of a yoke 49, that is held in position by the engagement of the T end 51 with lugs 50 upon the shaft 46 and a coil-spring 52, which holds the inking-rolls constantly 130 against the said printing-rolls. Any characters can be placed upon the periphery of the printing-rolls, which may be made of metal, rubber, cloth, or other like material that is used for printing.

Beneath the rear end of the swinging tray 25 is a shaft 53, supported in the outer ends of the arms 54 54, which project from the rock-shaft 55, journaled at either end in the side frames, which rock-shaft is actuated by a rock-arm 56, fixed thereto and adjustably connected with the lever 34 by a screw 57.

Upon the shaft 53 are a plurality of disks 58, separated by suitable collars, and near each end is a friction-roll 59, preferably of rubber, held between two of the said disks. Also fixed to said shaft are the two tray-disks 60 60, upon which the rear end of the tray 25 is supported. (See Fig. 4.)

The location of the printing-rolls 43 and the disks 61 upon the printing-roll shaft 44 is such that they are directly above the open spaces between the disks 58, so that when the shaft 53 is elevated and there is no ballot in the tray 25 the peripheries of the printing-rolls 43 and disks 61 will overlap the peripheries of the friction-rolls 59 and disks 58, the openings 26 in the tray permitting the said rolls and disks to pass each other.

Fixed to the shaft 13, directly over the friction-rolls 59, are two feed-rolls 62, having teeth cut around the peripheries thereof. As the ballot slides down from the chute 19 onto the swinging tray 25 the end of the ballot passes between the feed-rolls 62 and the friction-rolls 59 59 and the teeth in the feed-rolls grip the ballot and draw it through over the friction-rolls, imparting a rotary motion thereto and to the shaft 53, upon which they are secured.

Shaft 53 is elevated and depressed by the cam 37, the construction and operation of which is above described, through the lever 34, rock-arm 56, and rock-shaft 55—that is, the shaft 53 is in its lowest position when the parts are at rest and the cam-roll 39 is in the depression 38 in the cam-flange 40. When the cam-roll 39 is out of the depression and upon the concentric portion of the cam-flange, the shaft 53 is elevated, and so remains until a complete revolution of the cam 37 and the crank-handle has been made.

By rotating the screw 57 the position of the rock-arm 56, and through it the shaft 53, in relation to the lever 34 can be changed, and this adjustment varies the frictional contact between the friction-rolls 59 and feed-rolls 62 to accommodate paper or cardboard of different thicknesses. A shield 63 is fixed to a rock-shaft 64, supported at either end in the side frames, and projects upwardly, curving over the end of the tray 25 (see Fig. 4) and forming an end cover for said tray. While the shield is in its substantially vertical position a ballot cannot be dropped from the tray into the receptacle below, as the end thereof is effectually closed. The shield 63 is thrown down to the position shown by dotted lines in Fig. 4, removing the obstruction at the end of the tray after the shaft 53 has been partly elevated by the slotted link 64, joined to one of the arms 54 by the screw 65, which passes

through the slot therein, and the rock-arm 66, fixed upon the rock-shaft 64. Surrounding the rock-shaft 64 is a coil-spring 67, which is fastened at one end to the side frame 10 and at the other end to the rock-arm 66, the tension of said spring always tending to keep the shield in its upright position. It is apparent that when the arms 54 are elevated the screw 65 is brought into contact with the end of the slot in the slotted link 64 and the rock-shaft 64 is oscillated, and the shield 63, which is fixed thereto, is carried to its horizontal position and there held until the arms 54 again drop, allowing the spring 67 to return the rock-shaft and bringing the shield to its original upright position.

The registering mechanism comprises a train of indicating-wheels 68 68^a, loosely mounted upon a shaft 69, supported at either end in the side frames, the said wheels being separated by suitable collars upon the shaft, gears 70, fixed to said wheels, a pinion 71, fixed upon a shaft 72, parallel with the shaft 69 and meshing into the gear 70, and pinions 73, meshing into gears 68^a, fixed to one end of a sleeve 74, loosely mounted upon the said shaft 72 and having the two star-wheels 75 75 fixed to the other end. The star-wheels 75 75 have each three arms, and one of the wheels lies in the path of the pins 76, projecting from one side of the indicating-wheels 68 68^a, and the other in the path of the notch 77, also in the side of the indicating-wheels adjacent to the pins 76. As a partial rotary movement is imparted to the shaft 72 the pinion 71 causes the indicating-wheel 68 to advance one-tenth of a revolution, there being ten characters displayed upon its periphery. When the wheel 68 is completing the last tenth of its revolution, the arms upon the star-wheels 75, connected with the sleeve 74 in front of the next indicating-wheel, are brought into contact with the pin 76 and notch 77 in the next indicating-wheel, and the sleeve 74 and pinion 73 fixed thereto are given a partial rotation. This movement is conveyed to the indicating-wheel through the gear 68^a, which meshes into the pinion 73. This operation is continued throughout the whole train of indicating-wheels, the figures displayed being always visible through the glass plate 7. The shaft 72 is given a partial rotation for operating the indicating-train from the movement of the rock-shaft 46, which is only oscillated when a ballot is beneath the printing-rolls, through the non-rotatable longitudinally-movable sleeve 78, having a collar 79 thereon, and two star-wheels 80, fixed to the outer end, which engage at the proper time with a pin 81, projecting from one side of the cam 37 and a hole 82 through the shell thereof. (See Fig. 11.) Secure upon the pintle 87 to the vertical arms 83, fixed to rock-shaft 46, is the slotted plate 84, lying horizontally upon the top of the sleeve 78, with the collar 79 within the slot, as shown in Fig. 2. A bar 85, which is fixed to the plate 84 by the screw

86, extends under the said plate and sleeve 78 and prevents an upward displacement thereof. When the plate 84 and sleeve 78 are in the relative positions shown in Fig. 2, the registering-train will not operate or count. By rocking the shaft 46 the plate 84 is thrown outward by the vertical arms 83, and the collar 79, which rides against the inclined side of the slot in the plate 84, moves the sleeve 78 longitudinally until the arms of the outermost star-wheel are brought up against the shoulder 187 upon the cam 37. The arms of the star-wheels 80 now lie in the path of the pin 81 and hole 82 in the cam and when brought into contact therewith impart a partial rotation to the shaft 72 and through it to the indicating-train before described. The sleeve 78 is pushed back again to its original position and out of the path of the pin 81 and hole 82 by the cam-face 88 upon the cam 37, against which it rides as the cam is rotated. It is impossible to register more than one count for each revolution of the crank-handle by this mechanism, as the counting-sleeve 78 can only be given one partial rotation during a single rotation of the cam. The alarm mechanism is also actuated from the shaft 72, and hence only sounds when a ballot has been inserted and the indicating mechanism operated. It consists of a trip-wheel 89, secured to the shaft 72 and having pins 90 projecting laterally therefrom, a lever 91, pivoted to the side frame 10 and having a trip-arm 92 lying in the path of the pin 90, and a hammer-arm 93. As the trip-wheel 89 is given a partial rotation through the shaft 72 one of the pins 90 is brought into contact with the end of the trip-arm 92, which is forced down against the action of the coil-spring 94 until the pin rides off from the end of the trip-arm releasing it. The spring 94 now draws it back to its original position, and the hammer 95 upon the end of the hammer-arm 93 strikes the bell 96, which is secured to the side frame by a bracket 97. A ballot is dropped upon the chute 19, from which it slides onto the tray 25 until the end thereof is brought up against the shield 63. The ballot now rests upon the peripheries of the disks 58 and the friction-rolls 59 and beneath the feed-rolls 62 and printing-rolls 43. The box-tender now turns the crank-handle 14, and the guard 27 is thrown down over the chute, preventing the insertion of another ballot until the guard is again raised. The same movement of the lever 34 which throws down the guard also rocks the shaft 55 and elevates the shaft 53, and the ballot is now held rigidly between the faces of the feed-rolls 62 and friction-rolls 59. The ballot now covers the open spaces between the disks 58, and the printing-rolls 43, which rest upon the ballot, are given a slight upward movement, which rocks the shaft 46, and through the arm connections 83 the slotted plate 84 throws the sleeve 78 against the shoulder 79 of the cam 37. The same movement of the arms 54

which elevates the shaft 53 also throws down the shield 63, uncovering the end of the tray 25 and permitting the ballot to drop off therefrom into the receptacle below. It will be noted that this shield is never down until after the chute-guard is down and has closed the chute. While the crank-handle is being rotated, the feed-wheels 62 draw in the ballot 75 and the printing-rolls 43 print the cancellation-marks upon the back thereof. As before described, the rotation of the cam 37 actuates the indicating-train and the alarm mechanism when the sleeve 78 is thrown into engagement therewith, which only occurs when a ballot is beneath the printing-rolls and the shaft 46 caused to rock.

To insure the stopping of the crank-handle after each complete revolution, I have attached a stop-lug 189 to the side of the box in the path thereof, which lug is provided with a cam-shoulder 190 and a stop-shoulder 191. The handle 192 is provided with a finger 193 and is pivotally secured to the crank-handle 90 of the pintle 194. When the crank-handle is at rest, the finger 193 is against the stop-shoulder 191, and before it can be rotated the handle 192 must be tipped to the position shown by dotted lines in Fig. 8, releasing the finger from the stop-shoulder and allowing the same to be rotated. As the crank-handle is turned to its rest position the finger is brought up against the stop-shoulder 191 and obstructs its further movement. If perchance the handle 192 is tipped in relation to the crank-handle 14, the finger 193 will ride upon the face of the cam-shoulder 190 and throw the finger into line with the stop-shoulder.

The mechanism used to reset all of the indicating-wheels to zero consists of the following parts, which will be described only for one indicating-wheel, as the same parts are duplicated for each wheel. (See Figs. 4, 5, 6, and 7.) Fixed to one side of a gear 70 is a notched disk 95, having ten notches 96, or one for each character, upon the periphery of the wheel, which lies in the circular recess 97 in the side of the indicating-wheels 68. A constant frictional engagement between the gear 70 and the indicating-wheel 68 is maintained by means of the circular sheet-metal spring 98, which is sprung into a slit in the hub 99. This spring prevents the indicating-wheel from being carried too far by momentum. Upon the inside of the wheel 68, on the screw-stud 101, is secured a bell-crank 100, carrying at one end a pin 102, which extends through a hole 103 in the web of the indicating-wheel and lies normally in one of the notches 96. Also secured to the indicating-wheel by the screw-stud 104 is the click 105, having operative engagement with the stud 106 in the bell-crank through the slotted arm 107. A pin 108 is fixed in the shaft 69 and normally lies out of the path of the stud 109, projecting from the click 105; but when the shaft is given a slight endwise movement

the pin 108 is brought directly into the path of the said stud. For convenience in grasping the end of the shaft 69 I have attached thereto a knob, which has a pin 110 fixed thereto, which prevents the rotation of the shaft when the said pin is in the hole 111 in the side frame. To reset the indicating-wheels, the shaft 69 is pulled out to the position shown in Fig. 10, which brings the pin 108 into the path of the stud 109. The shaft is now rotated by means of the knob, and when the pin 108 meets the stud 109 the click 105 is swung upon the stud 104, operating the bell-crank 100 against the action of the spring 112, which raises the pin 102 out of the notched wheel, and thus separating the gear 70 and indicating-wheel. The continued rotary movement of the shaft 69 rotates the indicating-wheel 68 until the pin 76 is brought up against the stop-hook 114, which is so located as to present all the zero characters upon the several wheels in line with each other.

The stop-hooks 77 are suspended from a shaft 113, supported at either end of the side frames, and have a slight swinging movement thereon, the spring 115 holding them constantly in the position shown in Fig. 4. The rounded bottom ends of the hooks permit the pins 76 to force the hooks out of the way and to pass them when the indicating-wheels are moving in one direction.

There are many minor changes and alterations that can be made within my invention aside from those herein shown and described, and I would therefore have it understood that I do not limit myself to the exact construction herein shown and described, but claim all that falls fairly within the spirit and scope of my invention.

What I claim as new, and desire to secure by Letters Patent, is—

1. In a ballot-box, the combination with a frictionally - rotated canceling device, of a ballot-chute, leading thereto, a chute-guard for covering said ballot-chute, and means for actuating the same whereby the ballot-chute is entirely covered during the operation of the canceling device, substantially as described.

2. In a ballot-box, the combination with a

ballot-chute, of a swinging tray leading therefrom, canceling and registering mechanisms, means for actuating the same, a chute-guard, and means for actuating the same, whereby the ballot-chute is closed during the operation of the canceling and registering mechanisms, substantially as described.

3. The combination with the ballot-chute, of canceling mechanism, a hinged tray below said canceling mechanism, forming an extension of said ballot-chute, means for covering the said ballot-chute during the operation of the canceling mechanism, a registering mechanism, means for operating the same from a rock-shaft, and means for actuating said rock-shaft, the said means being operative only when a ballot is in the canceling mechanism, substantially as described.

4. The combination with canceling and registering mechanisms, in a ballot-box, of a ballot-chute, a swinging tray forming an extension of the said ballot-chute, means for actuating said tray, a shield covering the inner end of said tray, and means for actuating said shield whereby the same will uncover the tray end when the said tray is swung upon its mountings, substantially as described.

5. The combination in a ballot-box, of a ballot-chute, a chute-guard, a swinging ballot-tray, a shield for covering one end thereof, means for actuating the said chute-guard whereby the said ballot-chute is covered by the said chute-guard, and means for swinging said tray and rocking said shield, at substantially one and the same time, substantially as described.

6. The combination with a body member, of a crank-arm having a pivoted handle, and a stop-lug, secured to said body member in the path of said handle, whereby the said crank-arm is brought to a full stop at the termination of each revolution, and can only be released by moving said handle in relation to the said crank upon its pivot mountings, substantially as described.

In testimony whereof I affix my signature in presence of two witnesses.

CHARLES E. GIERDING.
